CLAIM

The ornamental design for a robot head, as shown and described.

DESCRIPTION

FIG. 1 is a front elevational view of a robot head, showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top and right side perspective view thereof;

FIG. 8 is a rear, bottom and left side perspective view thereof;

FIG. 9 is a front, right and bottom perspective view thereof;

FIG. 10 is a rear, left and top perspective view thereof;

FIG. 11 is a first reference view thereof, showing a non-limiting use of the robot head, attached to a body;
FIG. 12 is a second reference view thereof, showing a non-limiting use of the robot head in use, attached to a body;
FIG. 13 is a third reference view thereof, showing a non-limiting use of the robot head, showing how a portable information terminal such as a smart phone can be inserted;
and,

FIG. 14 is a fourth reference view thereof, showing a non-limiting use of the robot head in use, with a portable information terminal such as a smart phone inserted.

The broken lines seen in FIGS. 1-10 show portions of the robot head which form no part of the claimed design. The broken lines seen in FIGS. 11-14 are for the purpose of showing environmental structure, and form no part of the claimed design.

1 Claim, 14 Drawing Sheets
